TRAFFIC SIGNAL

John M. Kiniry, Satellite Beach, Anthony Finazzo, Indian Harbor Beach, and John R. Carroll, Satellite Beach, Fla., assignors to Tri-Vee, Inc., Satellite Beach, Fla.

Continuation-in-part of design application Ser. No. 12,234, June 6, 1968. This application Aug. 11, 1969, Ser. No. 18,631

Term of patent 14 years

Int. Cl. D29—99

U.S. Cl. D72—1

FIG. 1 is a front elevational view of the traffic signal embodying our new design.

FIG. 2 is a top plan view thereof.

FIG. 3 is a side elevational view thereof.

The traffic signal is shaded in FIG. 1 to indicate contrast.

This is a continuation-in-part of design application Ser. No. D12,234, filed June 6, 1968 and now abandoned.

We claim:

The ornamental design for the traffic signal, as shown and described.
